UNITED STATES PATENT OFFICE.

ALANSON H. MERRIMAN, OF WEST MERIDEN, CONNECTICUT.

PITMAN.

SPECIFICATION forming part of Letters Patent No. 224,207, dated February 3, 1880.

Application filed January 5, 1880.

To all whom it may concern:

Be it known that I, ALANSON H. MERRIMAN, of West Meriden, in the county of New Haven and State of Connecticut, have invented certain new and useful Improvements in Pitman Adjustments for Power-Presses, of which the following is a specification.

My invention relates to improvements in pitman adjustments in which an adjusting head or nut having a right-hand male screw at one end and a left-hand male screw at the other end forms the connection between the respective ends of the pitman. Said screws are received in female-threaded sockets split longitudinally and provided with transverse screws for firmly binding the sockets upon the threaded ends of the adjusting head or nut, as hereinafter described.

In the accompanying drawings, Figure 1 is a front elevation of a pitman adjustment which embodies my invention. Fig. 2 is a vertical section of the same on line *xx* of Fig. 1, and Fig. 3 is a transverse section of the same on line *yy* of Fig. 1.

25 A designates the upper end of the pitman, which is designed to be connected to the wrist-pin or eccentric of the main shaft, as in ordinary presses. B designates the lower end of said pitman, which is designed to be connected to the upper end of the ordinary gate or slide of the press in any ordinary manner. Each of the parts A B is split or divided longitudinally, and provided with a removable cap, C, which is held in place by transverse cap-screws *a a*. These parts are so divided that the caps C are upon one side of the axial line of the head or nut D, and the portion of the parts A B to which they are directly connected is upon the opposite side of said line. The confronting ends of the parts A B are bored out and provided with female threads, thereby forming a female-threaded socket in the parts A B. Said parts are adjusted to and from each other, and also connected together, by means of an adjusting head or nut, D, having a male screw at each end, the screw *b* having a right-hand thread, and the screw *c* having a left-hand thread. The respective sockets in the parts A B are correspondingly threaded.

50 The head or nut D is provided with pin-holes

for the insertion of a rod or lever to turn it by; but instead of pin-holes it may be made in angular form for the application of a wrench. The sockets are so fitted to the screws that when the cap-screws are tightened the caps 55 will be firmly bound upon the screws, instead of resting hard against the companion portions of the parts A B.

When it is desired to adjust the length of the pitman the cap-screws *a a* are loosened and 60 the adjusting-head and its screws turned until the desired adjustment of the pitman is effected. The cap-screws are then tightened to firmly bind the caps C C upon the respective ends of the screws *b c* and hold the parts rigidly together.

If desired, the parts A B might be simply slit up through the sockets, or for their whole length, and then provided with the same transverse cap-screws for binding the sockets upon 70 the respective screws; but the removable caps are far preferable, and possess some advantages not attained by the mere splitting of the sockets.

Some of the leading advantages of my adjustment are, that it is the nearest approach to an absolutely solid connection of any known to me. The caps can be readily detached for removal of the head and screws *b c* whenever desired. The slide or gate may be easily disconnected from the shaft and upper part of the pitman for removal by merely removing the upper one of the caps C. The device is very compact, and the head D does not project beyond the flush back side of the pitman, 80 (see Fig. 2,) so that the device may work upon the front vertical side of a frame. The tightening mechanism or cap-screws *a a* are upon the front side of the press, and accessible under all different adjustments.

I am aware that it is common to employ a right-hand and left-hand screw formed in one piece to adjust different parts to and from each other; also, that a pitman adjustment is shown in a prior patent in which externally and internally adjusting sockets having longitudinal slits were bound upon right and left handed screws at the respective ends of the pitman by means of tapering and internally-threaded sleeves, all of which are hereby disclaimed.

I claim as my invention—

1. In a pitman for a press, the head or nut D, having right and left male screws b c, in combination with the parts A B, having split 5 sockets correspondingly threaded, and the transverse adjusting-screws, substantially as described, and for the purpose specified.
2. The combination of the head or nut D, having right and left hand male screws b c,

the upper and lower ends of the pitman A B, to the removable caps C C, and cap-screws a a, substantially as described, and for the purpose specified.

ALANSON H. MERRIMAN.
